ATTORNEY

UNITED STATES PATENT OFFICE.

DANIEL F. MESSEY, OF KENNEBUNK, MAINE, ASSIGNOR TO L. WILDER
CHASE, TRUSTEE, OF HAVERHILL, MASSACHUSETTS.

LASTING-JACK.

SPECIFICATION forming part of Letters Patent No. 375,500, dated December 27, 1887.

Application filed February 14, 1887. Serial No. 227,587. (No model.)

To all whom it may concern:

Be it known that I, DANIEL F. MESSEY, of Kennebunk, in the county of York and State of Maine, have invented certain new and useful 5 Improvements in Lasting-Jacks, of which the following, taken in connection with the accompanying drawings, is a specification.

My invention relates to lasting-jacks adapted especially as a device to last felt boots; and 10 it has for its object the lasting of felt boots, or boots made of similar material, in a rapid, economical, and efficient manner.

Figure 1 represents in side elevation my lasting-jack with felt boot in section in its position on same, and Figs. 2 and 3 are respectively rear and front elevations of Fig. 1. Fig. 4 is an enlarged rear view of heel portion of lasting-jack, and Fig. 5 is a vertical central section of Fig. 4. Fig. 6 is a side elevation of 20 lasting-jack adapted to be operated by power, with one of the main-frame standards removed in order to show more clearly the power-driving mechanism. Fig. 7 is a front elevation of Fig. 6, with the lower portion of 25 one of the main-frame standards broken and removed to show more distinctly the power-driving mechanism.

The lasting-jack is made preferably of iron, except the last, which is made preferably of 30 wood, and the spring, which is made preferably of steel; but all the parts may be made of any suitable material, and the lasting-jack is designed to be bolted to the floor of the building in which it is used in order to secure 35 sufficient rigidity.

The main-frame standards 10 and 11 are bolted together by means of bolts, which perform duty as pivots for the links 12, 13, 14, and 15. The standards are held by said bolts 40 at such a distance apart as will permit the free movement between them of said links.

The front portion of the last 16 is adapted to receive pivotally, by means of bolts, the links 12 and 14 and connecting-rod 17. Its 45 upper front portion is provided with an offset, into which the rear portion of the toe-last 18 is designed to fit. The rear portion of the last 19 is adapted to receive pivotally, by means of bolts, the links 13 and 15 and connecting-rod 20. Its upper rear portion is ser-

rated, as shown on enlarged scale by Figs. 4 and 5. The connecting-rods 17 and 20 are pivotally secured by means of a bolt to the lever 21. One end of the lever is pivotally fastened, by means of a bolt, to fulcrum-stand 55 22. The other end of the lever is adapted to be operated by the foot-power of the operator. To the lever 21 is fastened one end of the spiral spring 23. The other end of the spring is fastened to one of the main-frame standards. 60

The arrangement, as shown, of the device is such that in operation, when a felt boot to be lasted is placed upon the lasting-jack, the operator, by pressing the lever 21 down with his foot, causes the front and rear portions of the 65 last 16 and 19 to be drawn down vertically by means of their being connected, as described, to the lever 21 by connecting-rods 17 and 20, and at the same time said front and rear portions, by reason of their being connected to 70 the main standard-frame 11 by the links 12, 13, 14, and 15, in a manner as shown and described, are projected horizontally, thereby stretching the boot. The function of the spiral spring is to pull up the lever and its connecting parts when the foot-pressure is removed from the lever. 75

The function of the serrated part of the rear portion of the last 19, by the repeated foot-pressure movement of the lever and its connected parts until the felt boot is sufficiently lasted, is to draw the felt boot onto the toe-last 18, and also to form the heel and other portions of the felt boot. 80

My lasting device may be operated by power 85 in any well-known manner. One style of power operation is shown by Figs. 6 and 7.

The upper portion of the device, except what is shown in Figs. 6 and 7, may be the same. The lower portion, as represented by 90 said figures, is made as follows: The connecting-rods 17 and 20 are pivotally connected to the sliding frame 24 by means of bolts. The lower portions of the main-frame standards are of a form, as shown, necessary to provide 95 room for the correct locating and operating of the power-driving mechanism. The crank-pulley 25, which is driven by belt or other suitable means of conveying power, is journaled in the bearing 26. It is also provided 100

with the crank-pin 27, which is adjustable within the crank-pulley in the usual well-known manner. To the crank-pin 27 is fitted the box 28, which is free to slide in the slot or way 29. The sliding frame 24 is guided by means of guide-slot 30 and pin 31 and guide 32. The device is what is sometimes called a "sliding cross-head" device, and its operation is as follows: When the crank-pulley is rotated, the crank-pin and box, by reason of their engagement with sliding frame, will cause the sliding frame to be reciprocated in vertical lines, and in use the result of its reciprocations, by reason of its connection with the upper 15 portion of the lasting-jack by means of connecting-rods 17 and 20, will be the same or nearly the same as if the lasting-jack were operated by the foot-lever mechanism, as shown by Figs. 1, 2, and 3. The crank-pin being 20 adjustable, the length of the stroke of the sliding frame may be governed.

The operation of my device used to last felt boots is as follows: A felt-boot bat, made in the usual manner by the deposit of wool sliver 25 upon a suitable former from a wool-carding

engine, is fulled and hardened in the usual manner. Then it is opened sufficiently to allow the toe-last to be placed in its position, and then it is subjected to the stretching and forming necessary, after which it is removed 30 from the lasting-jack and subjected to the usual methods employed to produce a finished felt boot—that is to say, it is treed and dried and trimmed.

What I claim as new, and desire to secure by 35 Letters Patent, is—

The last portion 16, provided with offset to receive toe-last, and last portion 19, provided with serrated heel, in combination with links 12, 13, 14, and 15, connecting-rods 17 and 20, 40 main-frame standards 10 and 11, lever 21, and spring 23, substantially as described.

In testimony whereof I have signed my name to this specification, in the presence of two subscribing witnesses, on this 31st day of January, 45

A. D. 1887.

DANIEL F. MESSER.
